US0D1087824S

(12) **United States Design Patent** (10) Patent No.: **US D1,087,824 S**
 Burgess (45) Date of Patent: ** Aug. 12, 2025

(54) **SCULPTURE OF MOTOR VEHICLE**

(71) Applicant: **Dr. Ing. h.c. F. Porsche Aktiengesellschaft**, Stuttgart (DE)

(72) Inventor: **James Burgess**, Stuttgart (DE)

(73) Assignee: **Dr. Ing. h.c. F. Porsche Aktiengesellschaft** (DE)

(**) Term: **15 Years**

(21) Appl. No.: **29/919,340**

(22) Filed: **Dec. 4, 2023**

(30) **Foreign Application Priority Data**

Jun. 5, 2023 (EM) 015023723-0001
 Jun. 5, 2023 (EM) 015023723-0002
